To all whom it may concern:

Be it known that we, Leslie Arthur Fountain and Douglas Phillips, both subjects of the King of Great Britain, Northern Ireland and the Isle of Man, residing at Cambridge Arterial Road, Enfield, in the county of Middlesex, England, have invented a new, original, and ornamental Design for a Combined Vacuum Tube Extractor and Terminal Pin Straightener, of which the following is a specification, reference being had to the accompanying drawings, forming part thereof:

Fig. 1 is a front perspective view of a combined vacuum tube extractor and a terminal pin straightener showing our new design;

Fig. 2 is a rear view of the terminal plug straightener side shown in Fig. 1;

Fig. 3 is a sectional view taken along line a—a of Fig. 2; and

Fig. 4 is a bottom view thereof.

We claim:

The ornamental design for a combined vacuum tube extractor and terminal pin straightener, as shown.

LESLIE ARTHUR FOUNTAIN.
DOUGLAS PHILLIPS.
